Primary Examiner — Karen E Kearney*Assistant Examiner* — John Reickel(74) *Attorney, Agent, or Firm* — Foley & Lardner LLP(57) **CLAIM**

The ornamental design for a display screen of a computing device with graphical user interface, as shown and described.

DESCRIPTION

The FIGURE is a front view of a display screen of a computing device with graphical user interface.

The broken line showing of a display screen and elements of the graphical user interface are included for the purpose of illustrating portions of the article and form no part of the claimed design.
